BY *Albert H. Spring*
Captain, A.S.C., R.C.
ATTORNEY

UNITED STATES PATENT OFFICE.

EARL H. SHERBONDY, OF CLEVELAND, OHIO.

MANUAL CONTROL FOR TURBINES.

Application filed August 1, 1918. Serial No. 247,853.

To all whom it may concern:

Be it known that I, EARL H. SHERBONDY, a citizen of the United States, residing at Cleveland, in the county of Cuyahoga and 5 State of Ohio, have invented certain new and useful Improvements in Manual Controls for Turbines, of which the following is a specification.

This invention relates to means for controlling a turbine.

The turbine in question is designed to be operated by the exhaust gases from an internal combustion engine and may be used to operate a centrifugal blower wheel to supply air under pressure for combustion in the engine.

In my co-pending case Serial No. 234,557 filed May 14, 1918 I have shown and claimed automatic means to control the speed of the 20 turbine, so that it will speed up and pump more air at higher altitudes. This automatic control however, is somewhat complicated and presents some liability to get out of order.

25 It is an object of this invention to provide a manual control means for the turbine, which is simple in design and which presents very little possibility of getting out of order. Other objects and advantages will appear 30 as the description proceeds.

In the drawings, Figure 1 is a side view of a turbine and control housing, partly in section; Figure 2 is a section on an enlarged scale on the line 2-2 of Figure 1; Figure 3 35 shows the manual control means and Figure 4 shows a modification.

Figure 1, indicates a turbine wheel mounted on the shaft 3 and provided with the usual buckets 2. Associated with the turbine, is a main casing element 4, annular in shape, being substantially shaped like a shallow dishpan. Associated with this casing is a backplate 5, which is attached at its outer edge to the casing 4.

45 Arranged within the casing 4, is an annular diaphragm 6, which defines an inlet chamber 7 and an exhaust chamber 8.

The fluid that is to operate the turbine is led thru suitable ports, (not shown in casing 50 4), into the inlet chamber 7.

After passing thru the turbine buckets, it passes into the chamber 8, from whence it escapes to the atmosphere, thru one or more exhaust pipes 9.

55 The diaphragm 6, is provided with one or more apertures in which are mounted one or

more valve seats 10. Seated on these valve seats, are valves 11. It will be apparent that when the valves 11 are open, the gases will be by-passed from the inlet chamber 7 to the 60 exhaust chamber 8, without having passed thru the turbine buckets. It is also apparent that the amount of gas passing thru the turbine buckets and consequently the speed of the turbine may be controlled by moving the 65 valves 11.

The stems 12 of the valves 11, move in bushings 13, which are mounted in a control housing 14. The other ends of the valve stems 12, are provided with discs 15. Arranged between the discs 15 and a bearing disc 16, is a spring 17, which tends to hold the valve 11 in its closed position and so tends to counteract the pressure of the 70 exhaust gases supplied to the turbine against 75 the right hand side of the valve 11.

Bearing against the discs 15 are cams 18 of the shape shown, mounted on a cam shaft 19. It will be apparent that when the cam-shaft is rotated in the direction of the arrow 80 in Figure 2, that the valves 11, will be opened, an amount proportional to the amount of rotation given to the cam-shaft.

The cam-shaft 19 is suitably mounted as shown in the control housing 14. This cam-shaft is intended to be rotated manually by any desired means. To this end it may be provided with a handle 20, which if convenient may be operated directly by hand, or it may be manually controlled from a distance, in any suitable way, such as by cranks and levers or as shown by a Bowden wire 21, controlled by a handle 22, which may be locked in any desired position on the segment 23.

95 Referring now to Figure 4, an oil control means for the valve stems 12 is shown. A control housing indicated generally at 24, carries walls, defining an oil pressure passage 25 and an oil waste passage 26.

The walls of the housing 24, further define a cylinder 27 in which moves a piston 28 that is rigidly connected to the valve stem 12.

A spring 17 serves the same purpose as in Figure 1. One side of the piston 28 is in 105 connection with the oil pressure passage 25, so that variation of this oil pressure will cause movement of the piston, against the movement of the spring 17. This oil pressure may be varied by a balanced valve 29, 110 which moves in a cylinder 30, mounted in a suitable recess in the control housing 24.

The valve 29 controls an oil passage 31, which is in communication with the oil pressure passage 25.

In the position shown in Figure 4, the oil passage 31 is closed with a valve 29 and the oil in the pressure passage 25, is at a high pressure, and the valves 11 are open.

As the valve 29 is moved upwardly, it gradually opens the passage 31 to relieve the oil pressure therein and allow the springs 17 to close the valves 11 and so speed up the turbine. The oil is drained from the inside of the cylinder 30, into the oil drain passage 26, thru a hole 32.

15 The valve 29 is held in its lower position, by spring 33, which is connected to the stem 34 of the valve 29, being held in position, by a cap 35, carried by a housing 24. The valve stem 34, has connected thereto a rod or 20 wire 36, with which it may be moved manually. This manual movement may be effected in any desired way, for instance, it may be controlled by a Bowden wire 21, which is manually controlled, as shown in Figure 3.

25 It should be understood that my invention may be carried out in a number of other ways, than as illustrated, as defined within the scope of the following claims.

I claim—

30 1. In combination with an exhaust chamber of a gas engine, an annular inlet chamber having a constricted outlet for a gas driven turbine, a gas driven turbine near said outlet, a turbine exhaust chamber for 35 said turbine having a wall contiguous to said annular inlet chamber, and a by-pass for the hot gases from said inlet chamber to the turbine exhaust chamber through said contiguous wall, a valve for said by-pass mounted in said turbine exhaust chamber, resilient means normally tending to seat said valve, the stem of said valve extending 40 through the non-contiguous wall of said turbine exhaust chamber, a disk fixedly secured to the extended portion of said valve stem, and manually controlled means operating said disk to control the position of said valve.

2. In combination with the casing of a gas 50 turbine, a partition dividing said casing substantially into an inlet chamber for the exhaust gases of a gas engine, with a constriction at one end, and a flaring exhaust chamber for a gas turbine, a gas turbine 55 with its periphery substantially in line with said partition at its constricting end, a by-pass in said partition, a valve for said by-pass, resilient means normally tending to seat said valve, valve supporting means for 60 said valved by-pass in said flaring exhaust chamber, the stem of said valve extending through the non-contiguous wall of said turbine exhaust chamber, a disk fixedly secured to the extended portion of said valve stem, and manually controlled means operating

said disk to control the position of said valve.

3. In combination with an exhaust chamber of a gas engine, an annular inlet chamber having a constricted outlet for a gas driven turbine, a gas driven turbine near said outlet, a turbine exhaust chamber for said turbine having a wall contiguous to said annular inlet chamber, and a by-pass for the hot gases from said inlet chamber to the turbine exhaust chamber through said contiguous wall, a valve for said by-pass mounted in said turbine exhaust chamber, the stem of said valve extending through the non-contiguous wall of said turbine exhaust chamber, a disk fixedly secured to the extended portion of said valve stem, resilient means normally tending to seat said valve, and manually controlled means operating said disk to control the position of said valve.

4. In combination with the casing of a gas turbine, a partition dividing said casing substantially into an inlet chamber for the exhaust gases of a gas engine, with a constriction at one end, and a flaring exhaust chamber for a gas turbine, a gas turbine with its periphery substantially in line with said partition at its constricting end, a valved by-pass in said partition, valve supporting means for said valved by-pass in 95 said flaring exhaust chamber, the stem of said valve extending through the non-contiguous wall of said turbine exhaust chamber, a disk fixedly secured to the extended portion of said valve stem, resilient means normally tending to seat said valve, and manually controlled means operating said disk to control the position of said valve.

5. In combination, a turbine casing comprising an inlet chamber, an exhaust chamber and a fluid actuated turbine therebetween, a by-pass between said inlet chamber and said exhaust chamber, a valve in said by-pass having its valve stem extending to a point without the inlet casing, a disk mounted on the extended portion of said valve stem, resilient means normally tending to seat said valve, and manually controlled cam means operating against said disk to control the position of said valve.

6. In combination, a turbine casing comprising an inlet chamber, an exhaust chamber and a fluid actuated turbine therebetween, a by-pass between said inlet chamber and said exhaust chamber, a valve in said by-pass having its valve stem extending to a point without the inlet casing, a disk mounted on the extended portion of said valve stem, manually controlled means operating against said disk to control the position of said valve, and a spring between said inlet chamber and said disk normally tending to seat said valve.

In testimony whereof I affix my signature,
EARL H. SHERBONDY.
